UNITED STATES PATENT OFFICE

CLYDE E. FULLER, OF ST. JOHNSBURY, VERMONT, ASSIGNOR TO E. AND T. FAIRBANKS AND COMPANY, OF ST. JOHNSBURY, VERMONT, A CORPORATION OF VERMONT

WEATHER SHIELD FOR TRACK SCALES

Application filed June 25, 1928. Serial No. 288,089.

This invention relates to railway track scales and more particularly to an improved means for covering the scale pits in which the scale mechanism is located to prevent the entrance of water, ashes and other foreign matter into the pit by way of slots in the pit cover through which the rail supports project.

In devices of the class referred to, as heretofore commonly constructed, the supporting means for the weather-shields are attached directly to the live rail supports, or stands. This necessitates stronger rail stands and the drilling of additional openings therein. It is accordingly an important object of this invention to provide an improved support for a weather shield which is adjustable along the entire length of the live rail, the construction being such that the support may be clamped in any position to the base flanges of the rail without the necessity of drilling openings therein.

Another object of this invention is the provision of a weather-shield construction which provides maximum accessibility to the rail supporting means whereby easy inspection thereof is permitted, the construction and arrangement being such that more of the rail supporting structure is exposed than is possible in the present type of weather-shields.

Other objects of this invention together with certain details of construction and combinations of parts, will be more particularly described in the specification and pointed out in the appended claims.

Referring to the drawings wherein is illustrated the preferred embodiment of this invention;

Figure 1 is a plan view of a portion of the covering, or deck, of a scale pit, showing several sections of the weather-shield in position;

Figure 2 is a vertical cross-sectional view of the deck, showing the arrangement of the scale supports;

Figure 3 is an enlarged vertical cross-sectional view through a live rail and the deck, showing the weather-shield and its supports in position; and

Figure 4 is a cross-sectional view taken on line 4—4 in Figure 3.

Similar characters of reference indicate corresponding parts throughout the several views of the drawings.

Referring more particularly to the drawings, there is shown a scale pit 10 in which the scale mechanism (not shown) is located. The pit is provided with a cover, or deck, 11 of any suitable construction which, in this preferred embodiment, comprises a flooring base 12 laid upon transverse beams 13, the ends of which rest upon shelves formed in side walls 14 of the scale pit. The flooring is waterproofed by covering it with any suitable surfacing material, such as roofing paper coated with tar.

The deck is provided with openings, or slots, 15 through which project the rail supports, or stands, 16 upon which are positioned the live rails 17. Mounted on the deck adjacent to the live rails 17 are the dead rails 18. The dead rails are also supported by the transverse beams 13. The live rails are of the usual construction, comprising a head 19, a web 20 and base flanges 21, 21 and are secured to the rail stands by any suitable means, as clamps 22 and bolts 23.

The openings 15 extend the full length of the deck and it is through these openings that water, ashes and other foreign matter will enter the pit and lodge upon the scale parts to the detriment of the operation and accuracy of the scale. To prevent this the present dirt- and weather-shield 24 is provided. The shield is formed of sheet metal sections of suitable length which may be joined or overlap each other in any convenient manner. To the underside of each section of the shield is suitably attached a plurality of bracket members 25 of angle iron construction having a base portion 26 and a depending portion, or flange, 27 in the lower edge of which is formed a groove 28 of inverted V-shape. The shield is of a width sufficient to overhang the adjacent edge of opening 15 and is provided along its outer edge with a depending skirt portion 29 which extends over and beyond an upstanding flange 30 of an angle plate 31 which is suitably fastened

100

to the deck 11 along the full length of the slot at the edge thereof. The flange 30 and the depending skirt 29 cooperate to prevent any matter from entering the scale pit and are spaced from each other for the purpose of providing adequate ventilation in order to prevent undue condensation of moisture from collecting on the scale mechanism.

A mounting for the shield is provided in the form of a bracket member 32. The brackets are fixed to the base flanges of the live rail in pairs, one on each side of the rail. The bracket consists of a single casting having an apertured base, or attaching portion, 33 from the center of which projects at a right angle thereto an angular shield supporting member 34. A slot 35 is formed in the supporting member 34, said slot being adapted to fit snugly over the base flange of the live rail. The free end is bifurcated to form a pair of ears 36, 36 having a web portion 37 between said ears. The web portion is edged and upon this edge the shield is fulcrumed, the shield being mounted thereon at an inclination to facilitate the shedding of water therefrom, as will be readily understood.

As has been stated above, the brackets 32 are clamped to the live rail in pairs, one on each side thereof, bolts 38 and lock-nuts 39 retaining the brackets in position. A spacing member 38' is threaded on bolt 38 between the attaching portions 33 of the bracket members. It will be understood that the construction outlined above provides a shield supporting and fulcruming means which may be clamped in any position along the length of the live rail without the necessity of drilling any openings therein or in any manner altering the construction thereof.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent of the United States is:

1. In a device of the character described, in combination, a scale deck having an opening therein, a plurality of rail stands projecting through said opening, a rail mounted on said stands, brackets mounted on said rail independently of said stands and a shield fulcrumed on said brackets.

2. In a device of the character described, in combination, a deck having an opening therein, a plurality of rail stands projecting through said opening, a rail mounted on said stands, brackets mounted for adjustment along said rail and a shield fulcrumed on said brackets.

3. In a device of the character described, in combination, a deck having an opening therein, a plurality of rail stands projecting through said opening, a rail mounted on said stands, brackets adjustably mounted on said rail independently of said rail stands and a shield fulcrumed on said brackets.

4. In a device of the character described, in combination, a deck having an opening therein, a plurality of rail stands projecting through said opening, a rail mounted on said stands, a pair of brackets clamped on said rail, one on each side thereof and adapted to be adjustable along said rail and shield fulcrumed on said brackets.

In testimony whereof, I have hereunto set my hand.

CLYDE E. FULLER.
